UNITED STATES PATENT OFFICE.

CHARLES N. TALBOT, OF NEW YORK, N. Y.

INDIVIDUAL SIGNALING APPARATUS.

SPECIFICATION forming part of Letters Patent No. 392,832, dated November 13, 1888.

Application filed July 19, 1888. Serial No. 280,402. (No model.)

To all whom it may concern:

Be it known that I, CHARLES N. TALBOT, of New York city, in the county and State of New York, have invented a certain new and useful 5 Improvement in Individual Signaling Apparatus, of which the following is a specification.

My invention relates to signaling systems of that character in which a number of signal-receiving devices are placed in the same circuit, and it is desired to operate or affect any one of such devices without affecting any of the others.

More especially my invention is intended to be used in connection with police-signaling systems, as a means whereby the attention of any policeman can be attracted from the police-station, so that he may know that the station desires to communicate with him and may proceed to his telephone-box and call up the 20 station.

The object of my invention is to produce an individual signaling system which shall be more effective and certain in its operation and less liable to error, and at the same time more simple in construction, than those heretofore employed.

To this end my invention consists in the various novel devices and combinations of devices employed by me in accomplishing the 30 above-named object, as hereinafter set forth and claimed.

My invention is illustrated in the accompanying drawings, in which—

Figure 1 is a side elevation of the signaling-transmitter; Fig. 2, a top view of the same with the break-wheel in section; Fig. 3, an end view of the contact-making brush; Fig. 4, a side view of one of the signal-boxes with the door removed; Fig. 5, a vertical section of 40 such box; Fig. 6, a cross-section of the box, with a top view of the devices within it; Fig. 7, a top view of the arm which operates the signal-wheel; and Fig. 8, a diagram of the circuits, showing the principal operating parts 45 of the transmitter and receiver.

The transmitter at the central station is enclosed in a suitable box, A. Within this box is supported the transmitting break-wheel, which consists of a body, B, of insulating material, having a metal rim, C, provided with a number of teeth, a, whose number corresponds to the number of signal-boxes on the

line. Upon one side of the insulating body B is a metal ring, D, provided with a similar number of notches, b. The break-wheel is 55 adapted to be revolved by clock-work, which may be placed in a box, E, and is connected with the shaft F of the break-wheel. Upon the shaft F is a sleeve, G, which extends outside the box A, and has a handle, H, for turning it. On the inner end of the sleeve G is secured an arm, I, which extends out beyond the rim of the break-wheel, and has on its inner side a tooth, c, which enters the notches b. When the arm is turned by hand, it passes 60 freely over the notches, but it is adapted to engage with said notches so as to turn with the wheel. Upon one side of the metal rim of the break-wheel a spring or brush, K, bears continually. At the other side of the wheel is 70 placed a spring, L, secured to the side of the box, which makes and breaks circuit with the break-wheel, according to whether it touches a tooth or passes over a notch of said wheel; also, secured to the side of the box is an arm, 75 d, on the upper end of which is pivoted a small bent metal lever, e, whose inner end is in the path of movement of the arm I, and whose outer end rests normally against a screw or pin, f.

Upon the surface of the break-wheel is placed a stop-pin, g. Pivoted on a standard within the box is a three-armed lever, h i k. To the arm k of the lever is attached a spiral spring, l, secured to the bottom of the box. The arm 80 i is adapted to engage the stop g for stopping the wheel. M is a sliding bar having a knob, N, outside the box for moving it, and carrying at its inner end a metal block, O, adapted to enter between two springs, m m. Pivoted 85 upon this bar is a piece, n, having at one end a catch, o, and provided with a spring, p, which keeps it in a raised position. At its other end the piece n has an inclined lower surface at q, adapted to slide over a pin, r, 90 which rises from the bottom of the box. Two different positions of these parts are shown by the two sets of dotted lines. At the transmitting-station I also provide a normally-open key, K, in a shunt around the break-wheel. 95

Each of the signal-receiving mechanisms consists of a box, P, provided with a hinged door, Q. Within this box is a disk, R, having a notch, s, in its edge. In each of the dif-

ferent signal-receivers the notch *s* is in a different situation on the rim of the disk, as is indicated in the diagram, Fig. 8. On the shaft of each disk *R* is a ratchet, *S*, with which engages a pawl, *t*, carried by an arm, *T*, journaled on the shaft of the disk and having an armature, *U*, at one end. This armature is placed in front of the poles of an electro-magnet, *V*. All the electro-magnets *V* are in series in circuit 1. Each signal-box has also within it a magnet, *W*, and all the magnets *W* are in series in a circuit, 2. Pivoted at *u*, below the magnet *W* in each box, is a lever, *X*, from which hangs a pin, *v*, adapted to enter the notch *s* of the wheel. At the long end of the lever is suspended, preferably, a shutter, *Y*, adapted to fall behind an opening in the box, which opening may be closed by a pane of glass, *Z*, so that when the shutter drops behind the opening a visual signal will thus be given to any one observing the box from outside. Instead of this, however, an audible signal may be given, as is illustrated in the right-hand apparatus of Fig. 8, in which the arm *Y* is adapted to close a local circuit, including a battery and a vibrating bell. It is evident that any desired number of signal-receiving devices may be included in the circuits, each having its notch *s* at a different point. The number of teeth of the ratchet *S* will correspond with the number of stations in circuit, and also with the number of notches *a* on the arm of the transmitting break-wheel and the notches *b* on the ring *D*. Each disk *R* is also provided with a unison-stop, *s'*, engaged by an arm, *r'*, extending down at one side from the lever *X*.

A main battery, *A'*, may be placed at the central station, which will supply current to the entire system.

Devices for resetting the parts of the signaling receiving apparatus after each one has been operated are attached to the door of each signal-box, so that the same will be operated by the movement of opening and closing the door. In the path of the shutter *Y* is a stop, *w*, secured to the side of the box, and immediately above it is a beveled projecting piece, *x*, extending transversely from an arm, *y*, extending inwardly from the door in the path of the shutter *Y*, in whose lower end is a small slot or opening, *z*. Extending from the shaft of the wheel *R* is an arm, *B'*, having a handle, *C'*, for moving it. In the bottom of the box is a sliding rod, *a'*, whose end bears against the door, and which carries a block, *b'*, and has coiled upon it a spiral spring, *c'*, whose tension keeps the rod constantly against the door. Near the free edge of the door and about the middle of its height a curved arm, *d'*, extends inwardly, said arm having at its inner end an incline, *e'*. Upon the upper side of this arm rests a rod, *f'*, which has on it a spiral spring, *g'*, forcing it down, and also carries a pin, *h'*, which extends over the short end of the lever *X*. Beneath the short end of this lever is a stop, *i'*, extending from the side of the box.

The operation of these devices is as follows: Normally the parts are all in the position shown in Fig. 8, the circuit 2 being open at *m m* and closed at *f*, so that the magnets *W* are not energized, and the circuit 1 being open at *I*, so that magnets *V* are also not energized, and the lever-arm *i* is against the pin *g*, so that the break-wheel cannot turn. Supposing the operator at the station desires to signal box No. 5, he closes the circuit 2 by drawing forward the bar *M*, so that the metal piece *O* enters between the springs *m m*, and by this same movement the catch *o* is brought against the lever-arm *h*, and the lever-arm *i* is thus withdrawn from the stop *g*, so that the break-wheel is free to move, and the clock-work having been previously wound up such wheel turns in the direction indicated by the arrow. As the bar is pulled out, the inclined end *q* of the catch-piece *n* slides over the pin *r*, so that by the time the bar reaches the limit of its movement its inner end becomes depressed and the catch is disengaged from arm *h*, whereupon the spring *l* will bring the arms *h* and *i* back to their normal position, in which said arm *i* is ready to engage again with the pin *g* when the wheel completes its revolution. Previous, however, to closing the circuit 2 and setting the break-wheel in motion, the operator moves the arm *I* down to a point corresponding with the number of the station he wishes to call—that is, wishing to call station No. 5, he moves the arm down a space equal to five teeth of the break-wheel. The closing of the circuit 2 causes all the magnets *W* to lift the lever *X* away from the disks *R*, and they are held there until the turning of the break-wheel brings the arm *I* around to the pivoted contact *e*. As the break-wheel turns, of course the circuit 1 is alternately opened and closed and a succession of impulses is given by the magnets *V* to the ratchets *S* and disks *R*. The movement of the disks *R* thus corresponds precisely with that of the break-wheel, and when the arm *I* has reached the contact *e* the disk *R* at the station for which said arm *I* was set will have turned so far that its notch *s* is under the pin *v* of the lever, while in all the other stations the notches will be otherwise situated. As soon as the arm *I* reaches the contact *e* and moves it circuit 2 is opened at *f* and the magnets *W* are all de-energized, so that all the levers *X* fall against the disks *R*; but at station No. 5, the notch *s* being opposite the pin, said pin falls into said notch and the shutter *Y* drops behind the opening in the box, or such other signal is made as the apparatus is designed to produce. The break-wheel continues to turn until the pin *g* strikes the arm *i* again, and of course the wheels *R* turn with it, and they are brought back to their normal or zero position, except the wheel of station No. 5, which is held by the pin *v* in the notch *s*. The revolution of the break-wheel having been completed, the operator may again break the circuit 2 by pushing the bar *M* in, at which time the in-

clined end of the catch o passes under the lever h without withdrawing the arm i . The signal is thus in position at box No. 5 to attract the attention of the policeman or other 5 person for whom it is intended, and the other signal-boxes are all in position to be operated in the same way without regard to the box already set.

It will be seen that the disks R provided 10 with the notches s form adjustable stops for the lever controlling the signal, such stops being all differently situated relative to their respective levers, and that such stops are adjusted by a step-by-step movement due to the 15 impulses communicated to the magnets V by the transmitting break-wheel.

When the policeman or other person observes the signal, he resets the same by first 20 opening the door of the box, whereby the piece x is withdrawn from the hole z in the shutter Y and such shutter is free to rise. It is, however, at such a distance from the magnet W as not to be attracted by said magnet. The opening of the door also releases the rod a' , so that 25 the spring c' forces the block b' into the path of the arm B' . At the same time the wedge d' is pulled out so that its inclined end e' comes under the rod f' , and such rod is forced down by its spring g' so that the pin h' strikes 30 the short end of the lever X and raises the long end of the lever and shutter Y , so that the latter is held up by pin h' . Then by means of the handle C the disk R is turned until the arm B' strikes the block b' , at which time the 35 notch s' is brought to the proper position relative to the pins v , and the signal-box is ready for another operation as soon as the door is closed again, which pushes back the rods a' , so as to move block b' from in front of arm B' , 40 and also pushes up rod f' , so as to release lever X .

It will be seen that there is no necessity for the policeman or other person to be informed as to the construction or operation of the apparatus, as he has simply to open the door, move the arm B' until he can move it no farther, and then shut the door again. After this 45 is done all the boxes will be in their original position, with the pins v all resting on the rims of the disks R .

Since it sometimes arises in the operation of devices of this character that one or more of the ratchets S will drop a tooth during its revolution, or the signal-receivers may otherwise 55 get out of unison, it is desirable to provide means whereby the transmitting operator may at any time and with certainty bring all the devices to unison, or automatic means may be provided for the same purpose. It is for this 60 purpose that I provide the pin s' and arm r' at the signal-receivers and the key K' at the transmitter.

It will be seen that when all the disks R are at their normal or zero position, and when all 65 the pins are resting on the rims of the disks, the arms r' ought all to be against the pins s' ; but in order that the operator may be assured

that this is the case and all the disks are in the right position, he may, by tapping the key K' , communicate impulses to all the magnets V , and any disks R which are not held from movement by the arms r' will be moved around until they are so stopped and held, whereby all the disks will be brought to the same position. When circuit is closed to the magnets W in beginning the operation of signaling, the arms r' are of course all raised away from the pins s' , so all the disks R are free to move in unison with the transmitting break-wheel.

What I claim is—

1. In individual signaling apparatus, the combination, with the signaling devices, each having a magnet, a signal-operating arm controlled by said magnet, and an adjustable stop for said arm, all said stops being differently situated relative to the respective arms, and a magnet adjusting said stop by a step-by-step movement, of the transmitting break-wheel in the circuit of said adjusting-magnets, having an adjustable automatic circuit-controller affecting the circuit of the signal-controlling magnets, substantially as set forth. 85

2. In individual signaling apparatus, the combination, with signal-receivers, each having a disk provided with a notch and all such notches being differently situated, a signal-operating arm whose movement is controlled by said notched disk, a magnet for moving said arm, and a magnet for adjusting said disk, of the transmitting break-wheel in the circuit of said adjusting-magnets carrying an adjustable automatic circuit-controller controlling the circuit of said signal-operating magnets, substantially as set forth. 95

3. In individual signaling apparatus, the combination, with signal-receivers, each consisting, essentially, of a signal-controlling lever, a magnet for moving said lever, an adjustable stop for said lever, all said stops being differently situated relative to the respective levers, and a magnet for moving said stops by a step-by-step movement, of the transmitting break-wheel, the adjustable projecting arm carried by said break-wheel, and the circuit-controller in the path of said arm controlling the circuit of the signal operating magnets, substantially as set forth. 105

4. In individual signaling apparatus, the combination, with signal-receivers, each having a notched disk and a signal-operating arm having a projection adapted to enter the notch or to rest on the rim of the disk, (all the notches being differently situated relative to the respective projections,) a magnet for lifting said arm off the disk, and a magnet in another circuit for turning said disk, of the transmitting break-wheel in the circuit of said turning-magnets and the adjustable automatic circuit-controller carried by said break-wheel and controlling the circuit of said lifting-magnets, substantially as set forth. 125

5. The combination, with the signal-receivers having adjusting-magnets in one circuit and signal-controlling magnets in another cir-

cuit, of the transmitting break-wheel in the circuit of said adjusting-magnets, and the arm sleeved on the shaft of said break-wheel and adapted to be brought into engagement with 5 said wheel, said arm controlling the circuit of said signal controlling magnets, substantially as set forth.

6. The combination, with the signal-receivers having adjusting-magnets in one circuit 10 and signal-controlling magnets in another circuit, of the transmitting break-wheel in the adjusting-magnets' circuit having a toothed metal rim and a notched ring on its surface, a contact-piece constantly in contact with said 15 rim, a contact-piece making and breaking circuit with the teeth thereof, the arm sleeved on the shaft of said wheel, and a projection on said arm adapted to engage with said notched ring, said arm controlling the circuit of said 20 signal-controlling magnets, substantially as set forth.

7. The combination, with the signal-receivers having signal-controlling magnets in one circuit, signals operating by gravity and held 25 up by the controlling-magnets, adjustable stops for said signals situated differently relative thereto, and magnets in another circuit for adjusting said stops, of the transmitting break-wheel in the circuit of said adjusting-magnets, 30 the adjustable arm carried thereby, and a normally-closed circuit-controller in the circuit of said signal-magnets and in the path of movement of said arm, substantially as set forth.

8. The combination, with signal-receivers 35 having signal-controlling magnets in one circuit, signals operating by gravity and held up by the controlling-magnets, adjustable stops for said signals situated differently relative thereto, and magnets in another circuit for adjusting said stops, of the transmitting break-wheel in the circuit of said adjusting-magnets, 40 the adjustable circuit-breaker operated by the movement of said break-wheel in the circuit of said controlling-magnets, and an additional circuit-controller in said circuit, substantially 45 as set forth.

9. The combination, with transmitting apparatus, of the signal-receivers, each inclosed in a box having a door, said door having inward 50 projections for resetting the signals, substantially as set forth.

10. In a signal-receiver, the combination of a box having a door, a dropping-signal therein, and a projection on said door adapted to 55 engage said signal and hold it down when the door is closed and to release it when the door is opened, substantially as set forth.

11. In a signal-receiver, the combination of a box having a door, a dropping-signal device, 60 and a spring for raising the signal, released by the opening of the door, substantially as set forth.

12. In a signal-receiver, the combination of a box having a door, a dropping-signal device, 65 a projection on the door adapted to engage said signal device and hold it down when the

door is closed and to release it when the door is opened, and a spring for raising the signal, released by the opening of the door, substantially as set forth. 70

13. In a signal-receiver, the combination of a box having a door, a dropping-signal arm or shutter having a slot or aperture, and a projection from the door having a beveled end in the path of the signal arm or shutter, substantially as set forth. 75

14. In a signal-receiver, the combination of a box having a door, a lever carrying at one end a signal arm or shutter, a spring-button above the other end of said lever, and a projection 8c on the door normally holding said button away from said lever, but releasing the same as the door is opened, whereby said button moves said lever to raise the signal, substantially as set forth. 85

15. In a signal-receiver, the combination, with the box P and door Q, of the lever X, signal arm or shutter Y, having the hole z, projection x on the door, rod f', spring g', pin h', and projection d', having the inclined end e', substantially as set forth. 90

16. In a signal-receiver, the combination, with the box having a door, of the notched stop-disk, the magnet for moving the same, and a movable stop for said disk controlled 95 by the movement of the door, substantially as set forth.

17. In a signal-receiver, the combination, with the box having a door, of the notched stop-disk, the magnet for moving the same, 100 and a spring-stop for said disk held out of engagement therewith by the closed door, substantially as set forth.

18. In a signal-receiver, the combination, with the box having a door, of the notched stop-disk, the magnet for moving the same, a handle on said disk for turning it, and a spring-stop held away from said handle by the closed door and entering the path of said handle when the door is opened, substantially as set 110 forth. 105

19. The combination, with the transmitting break-wheel and the clock-work for turning it, of the spring-stop for said wheel, the rod carrying a pivoted catch engaging said stop, and the handle for moving said rod, substantially 115 as set forth.

20. The combination, with the transmitting break-wheel and the clock-work for turning it, of the sliding rod provided with a handle, the 120 pivoted catch carried thereby, and the three-armed lever, one arm of which normally engages said break-wheel, while another is in the path of movement of said catch, and a spring attached to the third arm, substantially 125 as set forth.

21. In individual signaling apparatus, the combination of signal-receivers, each having a disk provided with a notch, and all such notches being differently situated, a signal-operating arm whose movement is controlled by said notched disk, a magnet for moving said 130

arm, and a magnet for turning said disk, the transmitting break-wheel in the circuit of said adjusting-magnets carrying an adjustable automatic circuit-controller controlling the circuit of said signal-operating magnets, unison-stops for said disks, and a unison circuit-controller in the circuit of said adjusting-magnets, substantially as set forth.

This specification signed and witnessed this 13th day of July, 1888.

CHARLES N. TALBOT.
